(57) **CLAIM**

We claim the ornamental design for an all-in-one information handling system display, as shown and described.

DESCRIPTION

FIG. 1 is a front perspective view of the all-in-one information handling system display comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear bottom perspective view thereof;

FIG. 9 is a rear upper perspective view thereof; and

FIG. 10 is a front bottom perspective view thereof.

FIG. 11 is a front perspective view of an alternative embodiment of the all-in-one information handling system display comprising the present invention;

FIG. 12 is a front elevation view of the alternative embodiment thereof;

FIG. 13 is a rear elevation view of the alternative embodiment thereof;

FIG. 14 is a right side view of the alternative embodiment thereof;

FIG. 15 is a left side view of the alternative embodiment thereof;

FIG. 16 is a top view of the alternative embodiment thereof;

FIG. 17 is a bottom view of the alternative embodiment thereof;

FIG. 18 is a rear bottom perspective view of the alternative embodiment thereof;

FIG. 19 is a rear upper perspective view of the alternative embodiment thereof; and,

FIG. 20 is a front bottom perspective view of the alternative embodiment thereof.

(Continued)

Broken lines shown in the drawings illustrate portions of the all-in-one information handling system display and form no part of the claimed design.
